UNITED STATES PATENT OFFICE.

THOMAS B. FERGUSON, OF HANFORD, CALIFORNIA.

WHEELED SCRAPER.

1,074,589.

Specification of Letters Patent. Patented Sept. 30, 1913.

Application filed October 9, 1912. Serial No. 724,772.

To all whom it may concern:

Be it known that I, THOMAS B. FERGUSON, a citizen of the United States, residing at Hanford, in the county of Kings and State 5 of California, have invented new and useful Improvements in Wheeled Scrapers, of which the following is a specification.

This invention relates to scrapers for excavating and moving dirt, and it has particular reference to an improved wheel 10 scraper, whereby the dirt may be conveniently moved a considerable distance, if necessary, before dumping.

The invention has for its object to produce a simple, durable and efficient carrying frame, whereby the loaded scraper may be supported without unduly straining any 15 of the parts.

A further object of the invention is to 20 support the scraper pivotally in such a manner that it may be conveniently tilted for the purpose of loading or unloading, as the case may be.

A further object of the invention is to 25 produce a simple and efficient wheel scraper wherein the act of inverting or upending the scraper to discharge the load shall be accomplished by direct draft of the teams, in such a manner as to avoid undue strain on the 30 frame and especially on the scoop supporting members.

A further object of the invention is to 35 produce a wheel scraper of a character which will enable the scoop to be conveniently manipulated to place it in position for being dumped and also in position for being restored to its initial or carrying position by the operator.

With these and other ends in view which 40 will readily appear as the nature of the invention is better understood, the same consists in the improved construction and novel arrangement and combination of parts which will be hereinafter fully described 45 and particularly pointed out in the claims.

In the accompanying drawings has been 50 illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a side elevation of the improved wheel scraper, showing the scoop in its initial or carrying position. Fig. 2 is a top plan view of the same. Fig. 3 is a sectional view taken on the line 3—3 in Fig. 2, showing the scoop tilted to a position for receiving or discharging the 55 load, as the case may be, and with dotted lines showing the scoop further tilted by means of the unloading lever. Fig. 4 is a sectional view taken on the line 4—4 in Fig. 2, showing the scoop in its discharging position to which it is carried by the draft of the team and showing also the unloading lever restored to its initial position to enable the inverting of the scoop to be accomplished. Fig. 5 is a sectional view similar 60 to Fig. 4, but showing the scoop started in the direction of its initial position by means of the unloading lever.

Corresponding parts in the several figures are denoted by like characters of reference. 75

The frame A of the improved machine includes rearwardly converging side members 1 serving to support between them a box or bearing member 2 for a vertical shaft 3 carrying a yoke 4 which supports a caster 80 wheel or trailer 5. The frame is supported on an axle 6 having transporting wheels 7.

Mounted on the parallel forward portions 8 of the side members of the frame forwardly of the converging portions 1, 1 and 85 in rear of the axle, are guides 9 which are preferably strongly constructed of angle iron by bending the same first to an approximate U-shape, and afterward bending the limbs to present an angle at about the 90 point where the guides are intersected by the side members 8. The lower ends of the slots 10 between the limbs of the guides will thus extend downwardly with respect to the side members 8 of the frame, while the 95 upper ends of the slots will be distinctly inclined in a forward direction, presenting inclined planes. The lower ends of the guide members are connected with the frame by means of truss rods 11, whereby the construction is strongly reinforced.

12 designates the scoop which may be constructed of sheet metal and of conventional shape; said scoop being preferably provided with a detachable blade or cutting member 105 13. By varying the width of the cutting

member the capacity of the scoop may be varied to some extent. The scoop is provided with trunnions 14 engaging the slots 10 of the guide members, and the parts are 5 so proportioned that when the scoop is in its normal or initial position with its bottom portion in an approximately horizontal position and with the trunnions supported at the lower extremities of the slots 10, the 10 scoop will be supported with its bottom portion clear of the ground, thus enabling the machine to be readily transported whether loaded or unloaded.

Mounted for oscillation on the axle 6 between the side members of the frame is a sleeve 15 having radially extending arms 16 which are connected with the sides or end members 17 of the scoop by means of links 18, said links being pivotally connected with 20 the side members 18 near the forward edge of the scoop. Supported on the frame A near the rear ends of the parallel portions 8 of the side members of said frame is a rock shaft 19 having radially extending arms 20 25 which are connected with the sides or end members 17 of the scoop by means of links 21, said links being pivotally connected with the end members 17 in rear of the trunnions 14 and relatively near the upturned rear 30 wall 22 of the scoop.

Pivotally connected with the trunnions 14 are draft rods 23 which are extended forwardly and guided through keepers 24 on the front cross bar 25 of the frame. Teams 35 may be attached to the draft rods 23 by means of eveners, not shown, and the frame is provided with a forwardly extending tongue, a portion of which is shown at 26.

The frame A includes a cross bar 27 40 which connects the side members of said frame at or near the angles between the forward parallel portions and the rearwardly extending converging portions of said side members, and supported on said rear cross 45 bar 27 and on the front cross bar 25 is an arch 28 longitudinally spanning the frame. Fulcrumed on said arch near the rear end thereof is the tilting lever 29 which is equipped with a stop member 30 of conventional construction adapted to engage a 50 segment rack 31 for the purpose of securing the tilting lever and related parts in adjusted position. The tilting lever is connected by a rod 32 with one arm of a lever 55 33 fulcrumed on the forward part of the arch, and the other arm of which is connected by a link 34 with an arm or crank 35 extending radially from the rocking sleeve 15, which latter may thus be oscillated. 60 Connected directly with the rock shaft 19 is an arm or lever 36 which, for convenience, I term the unloading lever, said lever being of a resilient nature, so as to enable a lug or stud 37 with which it is provided to be 65 placed into or out of engagement with any

one of a plurality of apertures 38 in a segment bar 39 which connects the arch member 28 with the rear cross bar 27. The latter cross bar supports a seat 40 for the driver or operator, and the rear portion of 70 the frame, bounded by the rear cross bar 27 and the converging side members 1, is provided with flooring 41 for the convenience of the operator.

The limbs or side members of the guides 75 9 are connected together and spaced apart at their upper ends by means of bolts 42 and spacing sleeves 43 that serve to obstruct the forward and upward movement of the trunnions 14 when the scoop is being tilted 80 or inverted in the act of unloading.

The parts of the machine are so proportioned and assembled that when the tilting lever is at the rearward limit of its movement and the unloading lever is at the forward limit of its movement, the arms 16 of the rocking sleeve 15 and the arms 20 of the rock shaft 19 will be so positioned that the links 18, 21 will support the scoop 85 with its bottom portion in an approximately 90 horizontal or level position, the trunnions 14 resting at the downward limits of the guide slots 10. It will be seen that the rocking sleeve 15 is actuated by the tilting lever through the medium of the lever 33 and its 95 connections.

By throwing the tilting lever 29 in a forward direction, the scoop will be tilted to place its cutting edge in engagement with the ground, the depth of the cut being regulated by the tilting lever. When 100 the machine is drawn in a forward direction by the teams attached to the draft rods 23, the scoop will be quickly loaded, and it may then be restored to its initial position by manipulating the tilting lever, after 105 which the load may be carried any desired distance to the place of deposit. In order to dump the load, the tilting lever is again manipulated to bring the cutting edge of the scoop into engagement with the ground, 110 and the unloading lever is thrown in a rearward direction to oscillate the rock shaft 19, thereby increasing the tilt of the scoop by lifting or elevating the rear portion 115 thereof. If desired, the discharge of the scoop may be delayed by locking the unloading lever at any point between the front and rear limits of its movement, in which event the load will be scraped over the surface of the ground until the dumping point 120 has been reached when, by releasing the unloading lever and permitting the same to swing to the rear limit of its movement, the draft of the teams, exerted directly on the trunnions 14 will cause said trunnions to 125 ride upwardly and forwardly over the inclined planes formed by the upper portions of the guide slots 10, until the scoop is practically inverted. During this portion 130 of the operation, the unloading lever must

be held by the operator clear of engagement with the segment bar 39 so that it will not become locked, this being necessary to permit the rock shaft 19 to oscillate forwardly, thereby permitting the scoop to be properly inverted to discharge the load and to be sufficiently lifted above the ground to clear the material just discharged. The machine may be returned to the loading point with the scoop inverted, as shown in Fig. 4, or the scoop may be previously restored to initial position. This is accomplished by first restoring the tilting lever to its initial position, thus carrying the cutting edge of the scoop forward and supporting it clear of the ground and then swinging the unloading lever to the rearward limit of its movement and releasing it to permit it to return to its initial position. By this movement of the unloading lever, the rear portion of the scoop will be carried through an arc, whereby the scoop is restored to its normal initial position, this last operation being greatly aided by the gravity of the scoop.

As will be seen from the foregoing description, the improved scraper is simple in construction and very easily manipulated, the several operations being performed in a natural and gradual manner, without the necessity of any great exertion on the part of the operator; the unloading operation especially being performed by the draft of the team. The machine has in practice been found to be thoroughly efficient for the purposes for which it is provided.

Having thus described the invention, what is claimed as new, is:—

1. In a machine of the class described, a wheel supported frame, rocking members mounted on said frame and having radially extending arms, slotted guides fixed on the frame, a scoop having trunnions engaging and riding in the slotted guides, links connecting the front end of the scoop with the arms of one rocking member, and links connecting the rear end of the scoop with the arms of another rocking member; in combination with draft members connected with the trunnions of the scoop to assist in moving the latter along the slotted guides.

2. In a machine of the class described, a wheeled frame, slotted guides fixed on the sides thereof, a scoop having trunnions engaging and riding in the slotted guides, rocking members supported on the frame in front and in rear of the scoop and having radially extending arms, links connecting the forward end of the scoop with the arms of the front rocking member, links connecting the rear end of the scoop with the arms of the rear rocking member, and means for independently operating the rocking members and for securing them at various adjustments; in combination with draft members connected with the trunnions of the

scoop to assist in moving the latter along the slotted guides.

3. In a machine of the class described, a frame having transporting wheels, angular slotted guides fixed on the side members of the frame, a scoop having trunnions engaging and riding in the slotted guides, means for tilting the scoop and for supporting it at various adjustments, and suitably guided draft members connected with the trunnions of the scoop to move the latter along the angular slotted guides.

4. In a machine of the class described, a frame having side members, slotted guides fixed on the side members, a scoop having trunnions engaging the slotted guides, rocking members supported for oscillation on the frame and having radially extending arms, links connecting the arms with the scoop, suitably guided draft members connected with the trunnions of the scoop, and means for independently operating the rocking members and for securing them at various adjustments.

5. In a machine of the class described, a frame having transporting wheels, slotted guides fixed on the side members of the frame, the upper ends of said guides being bent forwardly to present inclined planes, a scoop having trunnions riding in the slotted guides, suitably guided draft members connected with the trunnions, rocking members supported in front and in rear of the scoop and having radial arms, links connecting said arms with the scoop, and means for independently actuating the rocking members and for securing them at various adjustments.

6. In a machine of the class described, a frame, a wheel carrying axle supporting the front part of the frame, means for supporting the rear part of the frame, slotted guides fixed on the frame, a scoop having trunnions riding in the slotted guides, suitably guided draft members connected with the trunnions, a rocking sleeve supported on the axle and having radially extending arms, a rock shaft supported on the frame in rear of the scoop and having radially extending arms, links connecting the arms of the sleeve of the rock shaft with the scoop, and means for independently actuating the rocking sleeve and the rock shaft and for securing them at various adjustments.

7. In a machine of the class described, a frame, transporting wheels for said frame, angular slotted guides fixed on the frame, a scoop having trunnions riding in the slotted guides, suitably guided draft members connected with the trunnions to move the scoop along the angular slots of the guides, rocking members supported in front and in rear of the scoop and having arms extending radially in the direction of the scoop, links connecting said arms with the scoop in front

and in rear of the trunnions, a longitudinal arch spanning the frame, an adjusting lever fulcrumed on the arch, means connecting the adjusting lever with the rocking member in front of the scoop to oscillate said member, a lever connected with and extending radially from the rocking member in rear of the scoop, and means for securing the levers

and the parts controlled thereby at various adjustments.

In testimony whereof I affix my signature in presence of two witnesses.

THOMAS B. FERGUSON.
